PROJECTOR FOR USE ON A PLAYING SURFACE
Willis R. Morey, Arlington, Va., assignor to Mar-Bowl
Games, Inc., Washington, D.C.
Filed Nov. 20, 1964, Ser. No. 412,804
2 Claims. (Cl. 273—129)

The present invention comprises game player pieces and a compact package for holding and displaying the same, and includes a supporting base which holds selected player pieces, used in playing a variety of conventional games, and susceptible of use individually and collectively.

An object of the invention is to provide player pieces adapted for use collectively for playing games following rules furnished with the game package, certain of the game pieces being individually usable for amusement purposes.

In a preferred embodiment of this invention, the game pieces are packaged in so-called "transparent blister-packages." With most games played with these game pieces, a projector is used by a player, which is of special construction to, *inter alia*, automatically retain a projectile, such as a conventional marble, in predetermined proximity to a movable part of the projector controlled by the player and released by him to impel the projectile against a target, at the option of the player.

It is also within the contemplation of this invention to provide a card which carries the player pieces, for display purposes, with families of player pieces, such as marbles, simulated duckpins used in playing a variety of games, blister-packaged on the board surface and secured from displacement until removed for use.

Another object of the invention is to provide a projector which includes a self-leveling bed for the plunger of the projector to insure axial control of the plunger as it passes through the projector body in shooting a projectile against the selected target.

Other objects of the invention will be manifest from the following description of the present preferred form of the invention, taken in connection with the accompanying drawings, wherein:

FIG. 1 is a top plan view of a base upon which player pieces are mounted and secured, parts thereof being broken away to disclose details;

FIG. 2 is a longitudinal sectional view of a projector constructed in accordance with this invention, with a player piece or projectile shown thereon in dotted lines;

FIG. 3 is a vertical sectional view of the projector taken on the line 3—3 of FIG. 2, looking in the direction of the arrows;

FIG. 4 is a longitudinal sectional view of a duckpin or tenpin rack used in setting up the duckpins or tenpins which automatically positions the pins in proper position for playing;

FIG. 5 is a sectional view of the same, taken along the line 5—5 of FIG. 4 showing to advantage, the aft end of the rack with supporting legs and apertures in which the pins are placed to automatically, accurately position the pins on the playing surface;

FIG. 6 is a perspective view of a ball rack used for accurately positioning pool balls on the playing surface, the rack being removed, as in a conventional pool game, where a cue ball is shot thereagainst; and

FIG. 7 is an elevational view of a duckpin or tenpin which may be made of styrene or other suitable material.

In the present invention, a supporting base 10, made of cardboard or other suitable inexpensive material is used, upon which families of player pieces and appurtenances used therewith are blister-packaged in appropriate position for display purposes. A family of player pieces may consist of marbles 11, of different sizes if desired, which are compactly secured to the base 10 as indicated at 12.

2

The package is secured to the base and is transparent so that the player pieces can be seen therethrough in a fashion well known in the art. Another family of player pieces may be duckpins or tenpins 13 made of styrene or other suitable infrangible material, which are compactly mounted in a package 14 as illustrated in FIG. 1. Just as in the case of packaging the marbles, the duckpins or tenpins may be seen through the transparent blister package in which they are mounted and secured to the same surface of the support. It is of course to be understood that additional families of player pieces may be secured to the base for use in the playing of games of various miscellany.

For use in playing the games, it is also within the scope of this invention to utilize pin rack 15 and ball rack 16. When the racks are blister-packaged to the same surface of the support 10 as the game families, the rack 16 is superimposed upon the rack 15, both of which may be viewed through the transparent package 17 in which they are mounted. Both racks are made of styrene or like suitable material.

The base 10 has secured on the same surface as the families of game pieces and the racks, a projector 18 shown in FIG. 1. Detailed views of the projector are shown in FIGS. 2 and 3. The projector is adapted for use in playing games employing marbles and games employing duckpins or tenpins. The projector is preferably made of styrene and has an overall oblong configuration, one end of the body of which is depressed and slanted to provide a runway 19 adapted for the reception of a marble 11 or other projectile. Aft of the runway 19 is a supporting frame 20 for a plunger 21 which forms the impelling part of the projector. One end of the plunger is enlarged to provide a head 22, the outer face of which is concave, as indicated at 23, to provide a recess conforming substantially to the configuration of a marble or other rounded projectile which may be used in playing the game. The plunger is spring-loaded by employment of a helical spring 24 which is convoluted on the outer end of the plunger between the head 22 and the front wall of the frame 20. When the plunger 21 is retracted in the frame, the spring is compressed. Upon release of pressure from the handle end of the plunger, the expansive action of the spring projects the plunger head against a marble or the like, which has gravitated thereagainst in the runway 19, as illustrated to advantage in FIG. 2. In order to limit the forward movement of the plunger in the frame 20, an abutment 25 is formed on the plunger, as also illustrated to advantage in FIG. 2. The end of the plunger opposite to that upon which the head 22 is formed is reduced and the terminal provided with a finger-engaging enlargement 26. The frame 20 includes a rib 27 which issues upwardly from a horizontal portion 28 of the frame, midway between the sides of the latter. The top of the rib 27 is uniplanar with the bottom walls of the openings in the front and back walls of the frame, through which openings the plunger 21 passes when being retracted or released. By this arrangement, part of the plunger which passes through the frame 20 is held in a true horizontal plane to insure accurate projection of a marble 11 or the like in the direction of the target selected by the player.

The number of openings, designated 29 will correspond to the number of pins employed in playing a game of duckpins or tenpins. The diameter of each opening is slightly in excess of the diameter of the largest part of the body of the pin. Supporting legs 30 extend downwardly from the bottom face of the rack 15 to support the rack at the desired elevation and to provide ample clearance between the bottom of the rack and the surface upon which it is mounted, through which access

is gained to lift the rack in a vertical position to a point where it clears the tops of the pins.

All games may be played by shooting the marbles with projector or by hand shooting. Distances from the shooter line to the target may be varied according to the player's age. In bowling, for example, the pins should be placed 18 to 30 inches from the designated shooter line, book edges and a wall may be used as backstop for games played either on a table or on the floor.

In playing a game of duckpins or tenpins, the rack 15 is positioned on a playing surface and the pins then placed in the openings 29. After this, the rack is elevated to a point above the pins, leaving the pins in the position they would be in playing a conventional game of duckpins or tenpins. The projector 18 is then placed at a predetermined distance from the head pin and the player manipulates the projector on the playing surface until he has the projector in desired position for the selected area which he uses as a target, on the grouped pins. Of course, the projector must be completely behind a starting line, but may be moved laterally behind the line to permit positioning of the projector for impelling the marble against the selected target which may be one or more pins which remain standing after the initial shot has been made.

In shooting a game simulating pool, the balls or marbles are placed in rack 16 in the center of a circle approximately twelve inches in diameter, which may be drawn on carpet or on other cloth material and placed flat on a table surface. The players take one turn each, breaking up the marble formation and knocking marbles out of the circle. The winner is the player shooting the most marbles out of the circle.

It is to be understood that various changes may be made in this invention within the scope of the appended claims.

What is claimed is:

1. A projector including a one-piece body, a plunger slidably mounted in the body, a base member integral with said body of the projector and having a portion projecting beyond the forward end of said body, said portion having an inclined surface immediately before the forward end of said plunger inclined downwardly in the direction of said forward end relative to the longitudinal axis of the base whereby a projectile resting on said base will be gravity biased against the forward end of said plunger.

2. The projector of claim 1 wherein the plunger is spring-loaded, and a rib issues upwardly from the base, below an intermediate part of the plunger for stabilizing the latter while moving forward toward the projector by the expansive action of the spring.
